Des. 186,243
Patented Sept. 29, 1959

186,243

DENSITY MEASURING INSTRUMENT

Pernell J. Moore, Samuel John Hughes, Charles E. Vac-
lavik, and Glen M. Dunham, all of Houston, Tex., as-
signors to National Lead Company, New York, N.Y.,
a corporation of New Jersey

Application June 25, 1957, Serial No. 46,723

Term of patent 14 years

(Cl. D52—1)

FIG. 4.

FIG. 5.

FIG. 6.

FIG. 7.

Figure 1 is an elevational view of a density measuring instrument, showing our new design.

Figure 2 is a rear view of the instrument.

Figure 3 is a top view of the instrument.

Figure 4 is an end view of the instrument as seen from the left of Figure 1.

Figure 5 is an end view of the instrument as seen from the right of Figure 1.

Figure 6 is a cross-sectional view of the instrument taken along the line 6—6 on Figure 1.

Figure 7 is a sectional view of the instrument taken along the line 7—7 on Figure 1.

We claim:

The ornamental design for a density measuring instrument, as shown.
